UNITED STATES PATENT OFFICE.

NATHN LEVINE, OF BOSTON, MASSACHUSETTS.

FOLDING BED-LOUNGE.

SPECIFICATION forming part of Letters Patent No. 704,688, dated July 15, 1902.

Application filed February 24, 1902. Serial No. 95,209. (No model.)

To all whom it may concern:

Be it known that I, NATHN LEVINE, a subject of the Czar of Russia, residing at Boston, in the county of Suffolk and State of Massachusetts, have invented an Improvement in Folding Bed-Lounges, of which the following description, in connection with the accompanying drawings, is a specification, like letters on the drawings representing like parts.

10 This invention has for its object the production of a novel, simple, and efficient lounge-bed.

The particular features in which my invention consists will be hereinafter described 15 in the specification and fully pointed out in the claims at the end thereof.

Figure 1 is a side elevation of the lounge-bed with one fall elevated as represented in Fig. 2. Fig. 2 is an end elevation of the 20 lounge-bed shown in Fig. 1. Fig. 3 is a sectional detail in the line x , Fig. 2. Fig. 3^a is a detail showing the end of the leg e' . Fig. 4 shows an outside view of one of the end pieces with its two slots, to be described. 25 Fig. 5 is a cross-section in the line x^2 through one of the angle-irons constituting the ends of the fall. Fig. 6 is an enlarged view showing how the leg ends of the end pieces are bent to constitute rigid stiff legs. Fig. 7 is 30 a detail in plan view of part of the angle-iron b and connected springs. Fig. 8 is a detail of the end frame and angle-bar b . Fig. 9 is a detail of the outer end of the controlling-bar g .

35 In the production of my lounge-bed I take for the end frames A pieces of angle-iron and in a press bend the same into the shape shown in Fig. 2, providing the inturned flange a of the angle-iron with suitable slots a^x , as 40 represented, to receive the ends of the angle-bars b , to the edges of which within the upright legs A' of each end frame I connect suitable springs, as c , and to the inner ends of said springs I connect in any usual or suitable manner, as by plates c' , (see Fig. 1,) any usual wire-bed fabric—such, for instance, as represented in Fig. 1.

To stiffen the end frames and adapt them so that their lower ends constitute rigid legs, 45 I inturn the flanged part a' of the angle-iron, as represented at a^2 in Figs. 2 and 6, thus causing the inturned portion a^2 of the flange

a' to substantially contact with the flange a . This makes an exceedingly stiff leg for the end piece, and in the space left between the flanges a^2 , Fig. 6, I may insert usual pivots 55 a^3 of any suitable caster a^4 . The angle-bar b has one flange omitted for a distance from each end and its opposite ends b^2 extended through the holes a^5 , made in the flange a 60 of the angle-iron end pieces A, and to said ends I pivot at d the falls composed of the angle-irons d' , the ends of which are connected by an angle-iron piece d^3 by suitable bolts, as d^3 . Fig. 5 shows one of these angle-irons d' in cross-section, and it will be seen 65 that to one flange of the angle-bar is connected the springs c^x sustaining the wire or other fabric constituting part of the bed-bottom sustained by the falls.

The angle-iron parts d' and their connected angle-irons d^3 constitute the extensible sides of the bed-lounge, and said sides may be both maintained as at the right in Fig. 2 or may be both lowered in order that the bed-lounge may be used as a lounge, as represented 70 at the left, Fig. 2, or one may be left up and the other left down, as may be desired. Each end piece d' has jointed to it at e a leg e' , having a notch e^2 . The opposite end pieces A 75 are connected at each side the lounge by an angle-iron B, the connection being made by bolts B' , and the angle-iron B is connected with each side of the flange a of each end piece by suitable braces, as C, through bolts C'. 80

Each flange a of the angle-iron end pieces at the front and back of the lounge has secured to it by suitable bolts B' B^2 a plate f , said bolts being extended through two shims f' and f^2 , the space between the ends of the shims and the inner side of the plate and the outer side of the leg being entered by the controlling-bars g , each jointed by bolts g' to the opposite ends of a lever g^2 , pivoted at g^3 on each of the side bars B. Each of the controlling-bars g at its outer end is provided 90 with a handle g^4 , and the upper edge of each bar is notched and shaped to present an inclined surface g^x , as represented best in Fig. 1. A spring h , connecting at one end with 95 the lever g^2 and at the other end with the side bar B, acts normally to draw inwardly the bars g , they being prevented from being moved too far under the action of said spring

by means of the handle g^4 , contacting with the end frame.

To convert the lounge into a wide bed, it is only necessary to engage the falls described by hand and lift them into the position shown at the right of Fig. 2, and in this movement the legs e' are moved outwardly, the inner ends of said legs (see Fig. 3^a) being provided with inturned projections e^2 , that act as stops to limit the extent of upward movement of the falls. Whenever the stop meets the inner side of the flange a , the shoulder of the notch e^2 of the leg passes beyond the outer face of the end piece and immediately drops by gravity, causing said notch to engage the lower end b^x of the slot a^6 in the flanged part a , and in this condition the curved end e^6 of the leg rests in the notches g^x of the bars g . Now to lower the fall at one side of the lounge into position shown at the left in Fig. 2 either handle g^4 at either end of the lounge may be pulled, and in so doing the lever g^2 will be turned and the bar connected with the handle which is pulled will follow in the direction of the pull and the opposite bar will move outwardly or oppositely, and the inclined parts of the notches g^x of the bars will act upon the edge e^6 of the leg and lift the shoulder of the notch e^2 thereof upwardly, so that the weight of the fall will immediately cause the legs to pass through the slots a^6 into the full-line position, Fig. 2.

The flanged spring-sustaining bars b are secured rigidly to the opposite depending portions of the end pieces by means of suitable rivets 2, and lower down the end pieces are united by cross-bars h' , held in place by suitable rivets 3.

Having described my invention, what I claim, and desire to secure by Letters Patent, is—

1. In an apparatus of the class described, angle-iron end frames having in their side leg slots a^x , independent angle-iron bars sustained in said end frames and extended at their ends through said slots to the outer sides of said end frames, falls pivoted to the ends of said bars, the ends of said falls being composed of angle-iron bars, and mattress-supporting means sustained by said independent angle-bars and the angle-iron bars of the falls.

2. In apparatus of the class described, an-

gle-iron end frames having in their side legs two slots a^x and a^6 , independent angle-iron bars sustained in said end frames and extended at their ends through said slots to the outer sides of said end frames, falls pivoted to the ends of said bars, notched legs pivoted to said falls and free to be moved in slots a^6 of the angle-iron end frames, said notches being in engagement with said bars serving to keep the falls elevated, and longitudinally-movable bars having inclines to act against said legs to release the legs from their engagement with the end frames when it is desired to lower the falls.

3. In a lounge-bed, angle-iron end frames, angle-iron bars connecting said end frames, independent angle-iron bars sustained in said end frames below their upper ends, falls connected with the said independent angle-iron bars, a wire fabric sustained by said independent angle-iron bars and the angle-iron end pieces of the falls, and notched legs pivoted to the opposite ends of said falls, means to limit the distance to which said falls may be lifted, and leg-disengaging means comprising a lever having bars connected to its opposite ends, and a spring to retain said bars in a position to enable the legs of the falls to engage a shoulder and keep the falls elevated, longitudinal movement of each bar against the stress of said spring acting to release the legs and permit the falls to drop.

4. In an apparatus of the class described, angle-iron end frames having at each side two slots a^x and a^6 , and having one flange at each end of each end frame bent toward the other flange to constitute strong stiff legs, independent angle-iron bars extended through the slots a^x , falls having angle-iron ends pivoted to the ends of said independent angle-iron bars, notched legs pivoted to said falls and working in the slots a^6 , the notches of the legs engaging the end frames and retaining the falls outstretched, and longitudinally-movable bars to effect the disengagement of said legs from the end frames to enable the falls to be lowered.

In testimony whereof I have signed my name to this specification in the presence of two subscribing witnesses.

NATHN LEVINE.
